MUSICAL TELEPHONE TOY

Ernest J. Swimmer, 340 E. 52nd St. 10022, and Alan A. Hicks, 1349 Lexington Ave. 10028, both of New York, N.Y.

Filed June 14, 1966, Ser. No. 2,671

Term of patent 14 years

(Cl. D34—15)

The figure is a perspective view of a musical telephone toy showing our new design. The dominant features of our design reside in the full line portions shown. The back and sides not shown are plain and unornamental.

We claim:

The ornamental design for a musical telephone toy as shown and described.
